UNITED STATES PATENT OFFICE.

ISAAC L. DAVENPORT, OF CAMDEN, NEW JERSEY.

INK-FONT.

SPECIFICATION forming part of Letters Patent No. 768,522, dated August 23, 1904.

Application filed January 6, 1904. Serial No. 187,879. (No model.)

To all whom it may concern:

Be it known that I, ISAAC LEWIS DAVENPORT, a citizen of the United States, residing at the city of Camden, in the county of Camden and State of New Jersey, have invented 5 certain new and useful Improvements in Ink-Fonts, of which the following is a specification.

My invention has relation to an ink-font, 10 and in such connection it relates to the construction and arrangement of such a font.

The object of my invention is to provide 15 an ink-font having a large capacity, convenient to replenish, easy of access without change of position of the pen in the fingers, and constructed so that the pen may be inserted in the font without smearing of the ink on the fingers or penholder, said font having its outlet so protected that evaporation 20 is reduced to a minimum.

The nature and scope of my invention will 25 be more fully understood from the following description, taken in connection with the accompanying drawings, forming part hereof, in which—

Figure 1 is a vertical sectional view of an 30 ink-font embodying main features of my invention. Fig. 2 is a vertical sectional view of the front wall or cover with ink-cup attached of the ink - font. Fig. 3 is a sectional view of the buoyant funnel detached from the font, and Fig. 4 is a sectional view of the cap-funnel, detached from the font.

Referring to the drawings, 1 represents the 35 glass or similar reservoir, which may be made in various shapes, as desired. A recess is formed around the inside of the open end, as shown at 17. The detachable front or cover 15 for the reservoir 1 is preferably made of 40 hard rubber, having an inwardly-projecting flange or lip 14, designed to fit in the recess 17 of the reservoir 1. One mode of tightly securing the flange or lip 14 within the recess 17 of the reservoir 1 consists of a gasket 18 45 of yielding material, preferably soft rubber, which, as shown in Fig. 1, is placed between the body of the reservoir 1 and the flange 14 of the removable front or cover 15. Depending from the inner edge of the flange 14 50 is an inner wall or partition 3, which reaches

nearly to the bottom of the reservoir 1 and forms an air-chamber 4 between the said partition 3 and the front or cover 15, said air-chamber communicating with the reservoir at the bottom of the partition 3. The upper 55 portion of the front or cover 15 has an opening 5, provided with the stopper 6, which has a small vent-hole 7 through it. The ink-cup 8, attached to the lower portion of the front or cover 15, is bored out somewhat larger at 60 the top, as shown at 9, to serve as a clearance for the upper portion of the buoyant funnel 12. An opening 13 affords communication between the reservoir 1 and the ink-cup 8. The funnel 12 is made of buoyant 65 material and has a tubular extension 22, surrounding the outer periphery of the funnel and extending down nearly to the bottom of the tubular end 23 of said funnel and open at the lower end. The extension 22 is adapted 70 to fit loosely within the smaller portion of the ink-cup 8. A funnel-shaped stationary cap 10 is provided with a flange around the top and is shouldered underneath, as at 16, so as to engage in the top of the ink-cup, said 75 shoulder acting as a stop to the rise of the buoyant funnel 12. It will be understood that when the buoyant funnel 12 is in working position, as in Fig. 1, only the lower portion of the tubular extension 22 comes in contact with the inside of the ink-cup and the air-space 9 separates the upper end of the extension 22 from the cup 8, thus preventing 80 the upper portion from drying fast to the walls of the cup 8.

The operation of the ink-font is as follows: 85 The reservoir 1 is turned over on its back, the stopper 6 is removed, and the fluid poured through the opening 5 into the air-chamber 4, from which it flows over the end of the partition 3 into the reservoir 1. The stopper 6 is then replaced and the reservoir set on its bottom, when the air will enter through the vent 7 and pass under the bottom of the partition 3 into the reservoir, allowing the fluid 90 to flow out into the ink-cup until it reaches a level with the bottom of the wall 3, when the air-supply will be cut off, so that no more fluid can flow out of the reservoir 1. As the fluid rises in the ink-cup the confined air in 95 100

the tubular extension 22 will lift the funnel 12 until its top edge rests against the under side of the shoulder 16 of the cap 10. A slight pressure of the pen in the funnel 12 sinks the funnel 12 to the bottom of the cup 8, and the fluid in seeking its level runs up through the tubular end 23 into the funnel 12 proper, thus coming in contact with the pen. The cap-funnel 10 may be removed and the buoyant funnel 12 taken out at any time for cleaning, or the cup can be used with only the upper or cap funnel in place.

Having thus described the nature and object of my invention, what I claim as new, and desire to secure by Letters Patent, is—

1. The combination with an ink-reservoir having a shouldered or recessed opening in one of its walls, of a detachable front or cover having an inwardly-extending flange adapted to engage in the recess in the opening of the reservoir, an inner partition depending from the flange and adapted to separate the reservoir from the front or cover except near the bottom of the same, an opening through the upper portion of the cover provided with a stopper having a small air-vent through it, and an ink-cup attached to the lower portion of the cover and communicating with the bottom of the reservoir through an opening in the cover and partition.
2. The combination with an ink-reservoir having an opening in one of its walls, of a detachable cover or front, an inner partition located some distance from the front or cover and forming an air-chamber between the reservoir and said cover, said air-chamber communicating with the reservoir below the bottom of the inner partition, an opening through the upper part of the cover into the air-chamber provided with a suitable stopper, an ink-cup attached to the lower portion of the cover and communicating with the reservoir through an opening in the cover on a plane parallel with the bottom of the reservoir, a funnel depending within the ink-cup and adapted to slide loosely in said ink-cup, and a cap-funnel having a flat flange at the top adapted to

cover the top of the ink-cup, and shouldered underneath the flange to engage therein.

3. The combination with an ink-reservoir 50 having an opening, of a detachable front or cover adapted to engage tightly in the opening of the reservoir, an inner partition arranged on the inside of the cover and forming an air-chamber between the reservoir and the front cover, said air-chamber communicating at its bottom with the reservoir and at its upper part with the open air through the cover, an ink-cup attached to the lower portion of the cover and having a cylindrical 60 bore extending somewhat below the base of the reservoir, the lower portion of said ink-cup communicating with the reservoir through the front or cover, a clearance-chamber in the upper part of the ink-cup, a buoyant funnel 65 adapted to fit loosely in the ink-cup, and a cap-funnel having a flanged top, said cap-funnel shouldered underneath to engage the top of the ink-cup.

4. The combination with an ink-reservoir 70 having an opening, of a detachable front or cover for said opening, an air-chamber within the front or cover, the lower part of said chamber communicating with the reservoir and the upper part communicating with the open 75 air, an ink-cup attached to the lower portion of the front or cover and communicating with the reservoir through the front or cover, a buoyant funnel fitting loosely within the ink-cup, a clearance-space in the upper part of 80 the cup, and a stationary cap-funnel adapted to extend over the top of the ink-cup and to partly cover the buoyant funnel and shouldered underneath to engage with the top of the cup to constitute a stop to the rise of the 85 buoyant funnel.

In testimony whereof I have hereunto set my signature in the presence of two subscribing witnesses.

ISAAC L. DAVENPORT.
